UNITED STATES PATENT OFFICE.

SAMUEL G. CRANE, OF TOLEDO, OHIO, ASSIGNOR TO TOLEDO SCALE CO., OF TOLEDO, OHIO, A CORPORATION OF NEW JERSEY.

SCALE.

1,092,341.

Specification of Letters Patent.

Patented Apr. 7, 1914.

Application filed February 14, 1912. Serial No. 677,590.

To all whom it may concern:

Be it known that I, SAMUEL G. CRANE, a citizen of the United States, residing at Toledo, in the county of Lucas and State of Ohio, have invented certain new and useful Improvements in Scales, of which the following is a specification.

My invention relates to automatic illuminating devices and more particularly to a device of that class which may be used in connection with desks, scales, tables, safes, chairs, etc., whereby an electric lamp may be automatically lighted when weight is placed thereon, and automatically extinguished when the weight is removed.

The principal object is to provide a simple means which may be easily applied to any of the above articles so that when weight is placed on said article, an electric lamp will be lighted.

The object is accomplished by the construction herein described, claimed and illustrated in the accompanying drawings, in which:—

Figure 1 is an elevation of a scale provided with an illuminating device constructed according to my invention; Fig. 2 is a longitudinal section of the device; Fig. 3 is a plan view of the forward end of the casing of same; Fig. 4 is a rear end view of said casing; Fig. 5 is a detail plan view of the forward end of bar 19; Fig. 6 is an elevation of a modified form of the device; Fig. 7 represents in vertical section an additional form of the invention.

Referring more in detail to the parts:— In the scale shown in Fig. 1, 1 designates the main housing, 2 the chart frame, 3 the pan and 4 the adjusting screws, all of which are well known and hence not described in detail.

In accordance with my invention, electric lamps 5, carried by a reflector 6, are mounted, preferably above the chart 7 and at one side thereof, so that the light emitted by the lamps 5 may shine upon said chart. The reflector has an upwardly projecting portion 8, in one or both sides of which is mounted an opaque glass 9 having transparent letters 10. From the bottom of said reflector project supports 11 which are attached to the frame 2 by the usual screws 12, or in any preferred manner. The chart that is so illuminated is the one that is faced by the salesman, and hence in the shadow in a majority of shops.

The automatic illuminating device to be described is adapted to be placed beneath the scales in such a manner that one of the adjusting screws 4, of the scale, will rest thereon and comprises a lower casing member 13, having a bottom portion 14 and side portions 15, the forward ends 16 of which are beveled off to meet bottom portion 14. Cut in said beveled portions 16 are notches 17, which terminate above bottom portion 14, and in which lies the knife edged supporting member 18, of a beam 19, which latter is adapted to project beyond the rear of said casing 13 and receive a weight 20. The forward end 21 of said beam 19 is broadened and of less thickness than the body portion thereof and is provided with a slot 22 that is adapted to receive a ball 23. Covering said lower casing member 13 is a top casing member 24 which comprises a top portion 26 and side portions 27 that are adapted to fit on the outside of side portions 15 and be secured thereto by means of screws 28.

Secured to the lower side of top portion 26, by means of screws 29, are two pieces of insulating material, the upper one 30 of which extends unbroken practically the full length of top portion 24. Secured to the lower insulating member 31, by means of screws 31', is a spring 32, whose free end extends downwardly and backwardly and rests upon a piece of insulating material 33 that is secured to beam 19. Near the rear end of said insulating member 31 is secured a metal plate 34 by means of screws 35, one of which is slightly longer than the other for the purpose presently described. It will be seen that screws 31' and 35 are flush with the top of insulating member 31 and that insulating member 30 lies between said screws 31' and top portion 36 of upper casing member 24, so that they are perfectly insulated from each other.

Through one of each of side portions 15 and 27 are holes 36 that register and receive a bushing 37, through which the lead wires pass. Metal plate 34 is connected by a wire 38 to lamps 5, and spring 32 is connected by wire 39 with plug 40, the other wire 41 of which is connected with the lamps, the latter thus being in series with the circuit breaker. After proper electrical connections have been made the circuit breaker is placed beneath the scale so that one of the adjusting screws 4 on the side next to pan 3, rests

on ball 23. Plug 40 is screwed into an ordinary lamp socket and a weight placed in the scale pan. It will be seen that this additional weight will force end 21, of beam 19, downward, thus causing spring 32 to contact with one of screws 35, thereby closing the circuit. By moving weight 20 on beam 19, it will be seen that a very fine adjustment may be obtained, such as illuminating the chart 10 when a small fraction of an ounce is placed in the pan or when any predetermined weight such as one pound is weighed.

The above description refers to the preferred form of my device as applied to the 15 platform type of scales. In using the same in connection with a spring balance scale, or any article which may be suspended from above, a few slight modifications are necessary as shown in Fig. 6, in which the casing 20 member 24 is provided with laterally turned lugs 42 having apertures 43, so that the device may be secured to the ceiling or overhead support. Bar 19 is provided at its forward end with a hooked portion 44 from 25 which the spring balance is suspended.

As previously stated, the device may be applied to desks, safes, tables, chairs, etc., or to any object on which electric lights are used and upon which it is desirable to lower 30 the cost of current. For example, in using my device with a desk, I place in such a manner that one roller or leg will rest upon end 21. After proper electrical connections are made and lamps installed, it will be 35 readily seen that by laying the arm on the desk the lamp will be illuminated.

In using the device with safes, the operation is the same in that a slight pressure will illuminate the lamp. In this connection it 40 may be used as a protective device by either illuminating a lamp as a signal or producing an audible alarm.

While the forms heretofore described are the preferred constructions in which my invention 45 may be embodied, it will at once be apparent that a variety of other modifications may be made within the scope of my invention for effecting the same purpose. Thus for the weighted lever may be substituted its well known equivalent a spring 50 which might be of leaf form or, by making somewhat of a departure from the particular construction above shown and described, a spiral spring may be used. In Fig. 7 the latter construction is exemplified.

A telescopic casing comprises an internal member 45 and an outer member 46 which are permitted a slight relative axial movement by a screw 47 tapped into the wall of 60 the inner telescopic member and working in a slot 48 in the outer member. A spring 49 is compressed between the two members, the amount of normal compression being adjusted by a thumb screw 50 extending axially through the top of the inner member

and tapped therein and provided on its lower end with a seat 51 for the upper end of the spring. By adjusting the screw 50 the tension of the spring may also be adjusted within the required limits. The telescoping sections are formed of insulating material such as vulcanite and each of them is provided with a contact strip 52-53 secured thereto by a screw 54-55 and nut 56-57 coöperating therewith. Upon the outer end of the screws just mentioned are additional nuts 58-59 for securing the leading-in wires. The thumb screw 30 is formed at about the center of its head with a depression 59 to receive the ball 23 upon the adjusting screw 4.

It will be obvious from the above description that the spring may be adjusted through the screw 50 so that it will barely support the weight of the scale. Whenever 85 any additional weight is placed upon the scale the telescopic members will close slightly together until the inner and upper member rests upon the outer member, the contacts at the same time being brought into 90 touch to close the circuit and light the scale.

While I have disclosed the various forms of switch members therein entirely separate from the scales with which they are intended to operate, it will be apparent that if desired they may be attached to or brought upon the scale and many other changes will suggest themselves which may be made without departing from my invention.

It is apparent that in all of the above uses 100 that the cost of electric current will be greatly reduced and that sufficient light will be yielded for all necessary purposes.

Having thus described my invention, what I claim as new therein and desire to secure 105 by Letters Patent is:—

1. In an illuminating device for the indicating mechanism of a weighing scale, a yielding support for the scale, an electric lamp, and a switch in the lamp circuit adapted to be closed by pressure on the yielding support in excess of the weight of the empty scale thereon.

2. In an illuminating device for the indicating mechanism of a weighing scale, an 115 electric lamp, arranged adjacent the indicating mechanism of the scale, a switch in the lamp circuit adapted and arranged to be closed by a load placed upon the scale, and a yielding support normally sustaining 120 the weight of the scale imposed thereon to maintain the switch in open condition but yielding in response to a load imposed upon the scale to permit the switch to close.

3. In an illuminating device for the indicating mechanism of a weighing scale, the combination of one or more rigid supports for the base of the scale with a yielding support therefor adapted to be lowered by weight placed upon the platform of the 125 130

- scale, and a pair of contacts in circuit with the lamp which are normally open but closed when the yielding support yields to a load placed upon the platform of the scale. 5
4. In combination with a weighing scale, having a stationary housing, a dial or chart and movable platform parts, of an electric lamp arranged to light said dial or chart, and an automatic illuminating device actuated by said stationary housing and adapted to light said lamp when weight is placed upon said movable platform parts, substantially as specified. 10
5. In combination with a weighing scale, having a stationary housing, a dial or chart and movable platform parts, of an electric lamp arranged to light said dial or chart, an automatic illuminating device connected in series with said lamp which is adapted to close the circuit independently from the movable platform parts when weight is applied to said parts. 15
6. In combination with a weighing scale, having a stationary housing, a dial or chart and movable platform parts, of a reflector arranged above said dial or chart, a transparent sign in said reflector, an electric lamp beneath said reflector adapted to light said dial or chart and illuminate said sign, and an automatic illuminating device actuated by said stationary housing to light said lamp, substantially as specified. 20
7. In combination with a weighing scale, having a stationary housing, a dial or chart and movable platform parts, of an electric lamp arranged to light said dial or chart, an automatic illuminating device actuated by said stationary housing which is adapted to light said lamp when weight is applied to said movable platform parts and anti-friction contact between said stationary housing and said circuit opening and closing device, substantially as specified. 25
8. In combination with a weighing scale, having a stationary housing, a dial or chart and movable platform parts, of an electric lamp arranged to light said dial or chart, an automatic illuminating device actuated by said stationary housing to light said lamp, and means for adjusting said circuit opening and closing device, for the purpose set forth. 30
9. In combination with a weighing scale, having a stationary housing, a dial or chart and movable platform parts, of an electric lamp arranged to light said dial or chart, an adjustable automatic illuminating device adapted to light said lamp when actuated by said stationary housing through the agency of said movable platform parts, when a predetermined weight is placed on said movable platform parts. 35
10. In combination with a weighing scale, having a housing, a dial or chart and movable platform parts, of an electric lamp ar- 40
- ranged to light said dial or chart and an automatic illuminating device adapted to light said lamp and support said housing, dial or chart and movable platform parts, substantially as specified. 70
11. In combination with a weighing scale having a housing, a dial or chart and movable platform parts, of an electric lamp arranged to light said dial or chart and an adjustable automatic illuminating device adapted to support said housing, dial or chart and movable platform parts and light said lamp when a predetermined weight is placed on said movable platform parts, substantially as specified. 75
12. In combination with a weighing scale having a housing, a dial or chart and movable weighing parts, of an electric lamp arranged to light said dial or chart and an automatic illuminating device comprising a casing, a bar pivotally mounted in said casing, an adjustable weight on said bar and means on said scale housing for actuating said bar to light said lamp, substantially as specified. 80
13. In combination with a weighing scale having a housing, a dial or chart and movable weighing parts, of an electric lamp arranged to light said dial or chart and an automatic illuminating device, comprising a casing, a bar pivotally mounted in said casing, an adjustable weight on said bar, a flat spring insulated from said casing and from said bar, a metal plate insulated from said casing, said spring and said metal plate being electrically connected in series with said lamp, and means whereby said scale housing actuates said bar to contact said spring with said metal plate, substantially as and for the purpose set forth. 85
14. In combination with a weighing scale having a housing, a dial or chart and movable weighing parts, of an electric lamp arranged to light said dial or chart and an automatic illuminating device comprising a metal casing, an insulating strip secured within said casing, another insulating strip secured with said first named strip to said casing, a metal plate secured to said last named insulating strip, a flat spring also secured to said last named insulating strip and in the path of said metal plate, a bar pivotally mounted in said casing contacting with, but insulated from said flat spring, and means whereby said scale housing actuates said bar, for the purpose set forth. 90
15. A weighing scale in combination with a support therefor, comprising a yielding, supporting member adapted to partially support a scale and to yield to any additional weight placed thereon, a pair of contacts one of which is connected to the yielding member and adapted to be closed upon the other contact thereby, electric lamps for lighting the scale and connections from the 105
- 110
- 115
- 120
- 125
- 130

lamps to the source of current, said connections including the contact members.

16. In combination with a weighing scale having a base and a plurality of feet supporting the same, an electric lamp for lighting the scale, a switch in circuit with the lamp having a stationary and a yielding member, the latter extending under and supporting one of the feet of the base.
- 10 17. In combination with a weighing scale having a base and three feet connected to the base, a lamp for lighting the scale, a switch in circuit with the lamp and comprising a relatively stationary member and a

yielding member extending under one of the 15 feet of the scale.

18. In combination with a weighing scale having a base and a plurality of supporting feet, one at least of which is adjustable, a lamp for lighting the scale and a switch in 20 circuit with the lamp comprising a stationary contact and a yielding contact extending beneath and in contact with the adjustable foot of the scale.
